CATHODE RAY TUBE GUN STRUCTURE

David D. Van Ormer, Lancaster, Pa., assignor to Radio Corporation of America, a corporation of Delaware

Application July 1, 1953, Serial No. 365,309

7 Claims. (Cl. 313—82)

This invention relates to electron discharge devices of the cathode ray type and particularly to mount structures and means to support electrodes in such devices.

The electron gun structure of cathode ray tubes conventionally includes a cathode electrode, a control grid, an accelerating screen grid electrode, and a second accelerating electrode. These electrodes are normally formed of tubular members which are mounted successively along a common axis within a tubular neck portion of the cathode ray tube envelope.

The cathode electrode of such devices consists of a small tubular electrode which is closed at one end and is mounted coaxially within the tubular control grid electrode. The mounting of the cathode electrode is a ceramic disc to which the tubular cathode is fixed through an aperture at the center of the ceramic disc. The combined ceramic disc and cathode are mounted within the tubular control grid by locking the ceramic so that the closed end of the cathode is at a predetermined distance from one end of the control grid. The control grid at this end is closed by a transverse wall portion having a small aperture at its center aligned with the closed end of the cathode. This end of the cathode is coated with an electron emitting material to provide a source of electrons which are urged through the aperture of the control grid by the accelerating fields of the accelerating screen grid electrode which is spaced coaxially a short distance on the opposite side of the closed end of the control grid from the cathode electrode.

The electrostatic fields between these gun electrodes form the electron emission from the cathode into an electron beam directed substantially along the axis of the tubular neck portion of the electron beam path and on the end wall or face plate of a larger bulbous portion of the tube envelope. Deflecting means are normally provided for scanning the electron beam over the fluorescent screen in any desired manner, such as in a rectangular raster, for example.

The gun structure as described above is normally mounted within the tubular neck portion of the envelope by relatively heavy leads welded to the metallic portions of the tubular electrodes and to metal pins sealed through the end of the tubular neck end, which are in turn connected to the base pins of the tube. The structure thus described is of a conventional design and is well-known and is shown and described in greater detail in U. S. Patent 2,496,127 to Joseph Kelar.

Similar structures are used in cathode ray tubes used in television viewing picture tubes. However, with the trend toward television picture tubes of larger fluorescent screen area, the tendency is to also extend the length of the tubular neck portion of the tube envelope. However, the length of the front-to-back dimension of the cathode ray tube is limited from a practical standpoint by the size of the television cabinet in which the tube is to be mounted. It is desirable to keep the dimensions of such cabinets, from front to back, as small as possible so as to enable the cabinet to be passed through apartment-size

2

doorways, for example. Furthermore, a cabinet with small front to back dimensions is more desirable from an aesthetic point of view. One solution has been in providing a larger deflection angle of the electron beam.

5 However, another solution would also be to eliminate the spacing between the gun and the stem of the tube, which is occupied by the leads extending from the electrodes to the base pins of the tube.

Cathode ray tubes of the type described also have a 10 relatively inefficient cathode structure. The cathode material on the closed end of the tubular cathode electrodes is normally heated to thermionic temperatures by a double helical filament coil threaded into the open end of the tubular cathode. During tube operation heat radiated from the coil filament heats the tubular walls of the cathode electrode to a temperature at which sufficient heat is conducted by the cathode walls to the emitting end wall to provide a copious emission of electrons from the thermionic coating. Thus the cathode coating is 15 indirectly heated by heat conducted to it by the side walls of the tubular cathode. Furthermore, the contact between the tubular cathode wall and the ceramic support disc provides a loss of heat energy so that a cathode structure of the type described uses an excessive amount of 20 electrical energy. Standard cathode filaments used in the tubes of the type described require 0.6 ampere of current at 6.3 voltages or a heat dissipation of 3.78 watts. This amount of energy constitutes a relatively large drain of power from the circuit system of the tube. It is desirable 25 that such heater power be reduced to a minimum.

Cathode ray tubes of the type described also use 30 spacer elements between the cathode supporting ceramic disc and the apertured closed end of the control grid electrode to provide the predetermined cathode-grid spacing. 35 These spacers have taken the form of metal eyelets, annular ceramic insulators or the like. If the cathode to grid distance is critical, these spacers must closely conform by a small tolerance to the predetermined spacing distance. This requirement necessitates close inspection 40 of each spacer and a process of matching spacers of a certain size with cathode-ceramic assemblies of a specific size, since there are variations both in the spacers and in the mounting of the cathode within the ceramic. Such a procedure of matching a spacer to a cathode-ceramic member requires careful time consuming work.

45 It is, therefore, an object of this invention to provide a novel and simplified electrode structure for a cathode ray tube.

It is a further object of this invention to provide a 50 simplified and accurate mounting structure for a cathode-grid assembly in a cathode ray tube.

It is another object of the invention to provide cathode 55 ray tube having shorter front-to-back dimension.

It is another object of the invention to provide a cathode filament unit for a cathode ray tube utilizing a minimum of power output.

It is a further object of the invention to provide a cathode-grid assembly utilizing a simplified and accurate mounting structure.

60 The invention is in the structural design of a cathode control grid and accelerating grid assembly. The novel assembly comprises a supporting tubular accelerating electrode in which a pair of parallel disposed support plates of an insulating material are locked in place. Between the supporting plates there are fixed a control grid electrode and a tubular filamentary type cathode, the latter mounted transversely to the axis of the tubular accelerating support electrode.

65 Figure 1 is a partial sectional view of a cathode ray tube in accordance with the invention.

70 Figure 2 is an enlarged sectional view of part of the gun structure of the tube of Figure 1.

Figure 3 is a cross sectional view along lines 3—3 of Figure 2.

Figure 4 is a sectional view of part of the structure of Figure 1 at right angles to the section of Figure 1.

Figure 5 is a sectional view of a simplified gun structure utilizing a different form of the invention.

Figure 1 discloses a cathode ray tube which may be used for television viewing. The tube consists of an evacuated envelope having a large bulbous shell or cone-like portion 10 and a tubular neck portion 12 fixed to the bulbous portion. Within the tubular neck 12 is mounted an electron gun 14 for forming and directing a beam of electrons substantially along the axis of the neck portion 12 toward a fluorescent screen 16 formed on the inner surface of the end wall face plate 18 of the bulbous envelope portion 10.

Two pairs of coils are formed into a neck yoke 20 mounted on the envelope neck 12 for scanning the electron beam in any desired pattern over the surface of the fluorescent screen 16. The scanning coils are conventionally arranged with the coils of each pair connected in a series and mounted on opposite sides of the tubular neck 12. Each pair of coils is connected to appropriate sources of saw tooth currents for providing the scanning fields to move the electron beam in the desired raster pattern over the fluorescent screen 16. A focusing coil 22 may be used to focus the electron beam to a fine spot on the fluorescent screen during tube operation.

The electron gun of conventional cathode ray tubes normally consists of a plurality of tubular electrodes. The cathode of the gun comprises a small tubular electrode having one end closed by a solid wall portion upon which is formed a coating of electron emissive material such as a mixture of barium and strontium carbonates. The tubular cathode is mounted within a tubular control grid which is closed at one end by a solid wall having a small aperture at its center. The cathode is mounted with the coated end-wall of the cathode closely spaced from and aligned with the central aperture of the control grid. The gun also is normally formed with a plurality of tubular accelerating electrodes spaced along a common axis and having apertures therethrough aligned with the central aperture of the control grid for the passage therethrough of the electrons from the cathode in the form of a beam. Electron guns of this type are shown and described in greater detail, for example, in the above cited patent to J. Kelar 2,496,127.

In accordance with the invention, however, the electron gun 14 is provided with a simplified and novel electrode arrangement. As shown in Figures 2, 3, and 4, the cathode electrode consists of a tubular member 24 which is mounted on and extends between two parallel sheets of mica 26. Furthermore, the tubular cathode 24 is enclosed in an open ended box construction 28 having at the ends thereof tabs 30.

The box construction 28 forms the control grid of the gun and is also mounted on and extends between the mica sheets 26. The micas are locked together by extending the tab portion 30 through appropriately formed holes in the mica and offsetting the tabs slightly to prevent their withdrawal from the micas. The assembly forms a rigid box structure in which the sides of the box are formed by the tubular grid member 28 and the ends of the box by the two mica plates 26.

The mica grid assembly 26—28 is mounted within a tubular accelerating electrode 32. A metal diaphragm or wall portion 34 is fixed by welding, for example, across one end of the tubular accelerating electrode 32 as shown in Figure 2. The diaphragm 34 is spaced a sufficient distance from the adjacent end of tubular member 32 to provide a cup-like structure at that end.

As shown in Figure 3, the mica plates 26 are dimensioned so that when they are fixed to the grid box structure 28, they will slip tightly into the tubular electrode

32 to rigidly hold the mica-grid assembly 26—28 within the tubular member 32 and will prevent lateral displacement of the assembly within the tubular member 32. A retainer ring 36 is slipped into the open end of the tubular member 32 and into engagement with the adjacent ends of the mica sheets 26 at which point the ring 36 is welded or locked by other means to support member 32 to hold the grid-mica assembly 26—28 in position and to prevent any axial movement thereof.

Opposite side walls of tubular member 32 are cut away as shown at 38, for example, on both sides and in alignment with the ends of the tubular cathode 24. The openings 38 allow the mounting of the cathode 24 into the mica-grid assembly after the assembly has been fixed within the tubular accelerating support member 32. Cathode 24 is mounted in openings punched through mica sheets 26 to fit cathode 24 tightly. Also the openings 38 permit passing of lead 40 to the cathode 24. Within the tubular cathode 24 there is positioned a folded filamentary cathode filament 44 for raising the temperature of the cathode to thermionic temperatures. The leads 46 of the cathode filament 44 are also brought out of one of the openings 38 in member 32 and fixed to appropriate base pins 48 extending through the press or closed end 47 of the tubular neck portion 12. A lead 42 passes through a central opening in retainer ring 36 to the control grid box 28. Cathode and grid leads 40 and 42 are also fastened to other base pins 48 respectively. The pins 48 extend through the press 47 and are connected to pins 49 fixed into the tube base 50.

The outer surface of the tubular cathode electrode 24 is coated with electron emitting material such as a mixture of barium and strontium carbonate to provide a source of electrons within the tube. Aligned with a coated surface of cathode 24 there is an aperture 52 in the top of the grid box 28 to provide passage therethrough of electrons from the cathode surface. The accelerating electrode diaphragm 34 also has formed at its center an aperture 54 in alignment with aperture 52 and the coated cathode surface.

Spaced along the axis of tubular member 32 is a second tubular accelerating electrode 56 for providing a high positive potential gradient in the beam path and to accelerate the electrons emitted from cathode 24 to high velocities. Tubular electrode 56 is closed at its opposite end by an apertured diaphragm or wall portion 58. Mounted at the edges of the diaphragm 58 are spring fingers or spacers 60 for positioning the end of the accelerating electrode 56 on the axis of the tubular neck portion 12. Also the spring fingers 60 make electrical contact between electrode 56 and a conductive wall coating 62 extending from the end of electrode 56 to a point adjacent the fluorescent screen 16 of the tube.

The operation of the tube is that in which current passing through filament 44 heats tubular cathode 24 to a temperature at which electrons are freely emitted from the cathode coating. The control grid electrode 28 is normally operated at a range of potentials negative to the potential of the cathode 24. The accelerating electrode 32, however, is operated at a potential of several hundred volts positive to cathode 24, while electrode 56 is operated at the highest potential in the order of from 1 to 18,000 volts depending upon the use and size of the cathode ray tube. As is well known, the negative potential of electrode 28 can be varied until the positive accelerating potential of electrode 24 will extend through aperture 52 and pull electrons emitted from the cathode coating through aperture 52. These electrons are accelerated through aperture 54 into the tubular electrode 56.

The difference in potential between electrodes 32 and 56 provides an electron lens field which aids in forming the electrons into a beam. The beam electrons, however, are diverging in their passage through the tubular electrode 56. The field of the focusing coil 22 provides a converging action on electrons of the beam and causes

them to converge or become focused to a small well-defined beam spot on the surface of the fluorescent screen 16. The voltages shown in Figure 2 represent those which have been applied to the respective electrodes during successful operation of a tube of the type described. However, these values need not be limiting.

The adjacent ends of electrodes 32 and 56 are cut at an angle to the common axis of these electrodes, as shown in Figure 2. This has the effect of tilting the lens field between electrodes 32 and 56 so that the beam electrons passing into this field are bent from their axial beam path in the direction of the axis of the tubular envelope member 12. A magnet 66 mounted on the tubular neck portion 12 provides a magnetic lens field for bending the beam back onto the axis of the neck 12 and to direct the beam through the apertured diaphragm 58 at the end of the tubular electrode 56. The arrangement provides a means for trapping the negative ions formed within the electron beam. This does not constitute a part of the invention and is more fully described in the copending application of L. E. Swedlund, Serial No. 130,775 filed December 2, 1949. Furthermore as part of the ion trapping arrangement, the electrodes 32 and 56 mounted on a common axis are inclined at a small angle to the axis of the tubular neck portion 12.

The novel electrode mounting arrangement, as described above and consisting of electrodes 24, 28 and 32 provides an assembly which can be both simply and accurately made. Mica can be accurately cut and punched to very close tolerances. Accordingly, mica plates 26 can be accurately cut to provide the correct spacing between cathode 24 and the control grid aperture 52 to within very close limits. Furthermore, the spacing between the control grid aperture 52 and the accelerating diaphragm 34 can be accurately maintained from tube to tube and within the required limits. Thus the assembling of the electrodes 24 and 28 to the mica spacer elements 26 can be done easily and accurately. The mounting of this cathode grid assembly within the accelerating electrode support 32 can be accomplished easily and without any loss of accuracy in electrode spacing.

By bringing the leads 40 and 46 of the respective electrodes through the side wall of support electrode 32, it is possible to mount the electron gun 14 closer to the press 47 of the tube. This results in a shorter tube neck, which is of an advantage in large tubes where the screen-to-stem dimension becomes critical.

An additional advantage of the structure described is the ability to use a filamentary folded heater within the cathode 24 in place of the reverse wound coil heaters conventionally used. The difficulty of using a tubular cathode having the emitting surface on a closed end of the cathode, as described above, is the necessity of using an excess amount of power in order to raise the temperature of the tubular cathode sufficiently high to heat the coating at the closed end to thermionic temperatures. However, the structure shown in Figures 2 and 4, for example is that in which the filament 44 is in direct contact with the cathode wall upon which is coated the thermionic material. This provides a much more efficient manner of heating the electron emitting coating and enables the use of a much less power. Furthermore, there is little loss of heat to the mica supports 26, as was true with the conventional type cathode mounted in a heavy ceramic near the emitting end thereof.

The electrode 28 may be formed as a single piece and wrapped around to form its boxlike structure. The bottom of the box or the side 29 of electrode 28 opposite from the grid aperture 52 forms a light shield to prevent a light from the heated cathode 24 from being directed onto the glass surfaces of the press 47 and in turn being reflected down the tube neck 12 onto the fluorescent screen 16. Grid 28, however, need not be made from a single piece wrapped into the desired shape, but may be made of a plurality of metal sheets if desired.

Figure 5 shows an adaptation of the invention of Figure 2 in which some features of the invention can be used in a triode type cathode ray tube. In Figure 5, the mica sheets 26 are locked together by metal plates 68 and 70 on the top and bottom respectively and by side plates 72, of which only one is shown. The tabs 74 corresponding to tabs 30 of Figure 2, for example, extend through the micas 26 from each of the electrode plates 68, 70 and 72 and are bent or twisted to rigidly lock the plates 68, 70 and 72 to the mica sheets 26 to form a rigid box structure. A cathode 24 of the type described in Figures 2 and 4 is mounted in a similar manner through the mica strips 26 and has its outer surface coated with an electron emitting material. The 10 coated surface of cathode 24 is mounted in a predetermined spacing from an aperture 76 in plate 68. This cathode-grid-mica assembly is mounted on base pins 48 by welding the pins 48 directly to the plate structures of the assembly and also by the leads 75 which extend from the filament 44, the cathode 24 and plate 68 to the several base pins 48. The accelerating electrode of the tube of this type consists merely of wall coating 60 which is extended down the neck 12 of the tube envelope to overlap the grid plate 68. The operation of the tube 15 is of the type disclosed in the above cited application to L. E. Swedlund.

While certain specific embodiments have been illustrated and described, it will be understood that various changes and modifications may be made therein without departing from the spirit and scope of the invention.

What is claimed is:

1. An electron gun for a cathode ray tube, said electron gun comprising, a tubular electrode, a pair of support members of electrically insulating material supported within said tubular electrode, a tubular cathode electrode supported within said tubular electrode transversely to the axis of said tubular electrode and by said insulating support members, and an apertured plate electrode supported by said insulating support members 35 within said tubular electrode and adjacent said cathode electrode.
2. An electron gun for a cathode ray tube, said electron gun comprising, a tubular electrode, a first apertured metal plate member fixed within and transversely across said tubular member, a pair of support members of electrically insulating material mounted within said tubular electrode on opposite sides of the axis thereof in contact with said transverse metal plate member, a tubular cathode electrode supported within and transversely to the axis of said tubular electrode and by said insulating support members, and a second apertured metal plate member supported within said tubular electrode by said insulating support members between said cathode electrode and said first metal plate member.
3. An electron gun for a cathode ray tube comprising, a tubular electrode, a first apertured plate member fixed within and closing said tubular electrode adjacent one end thereof, a pair of support plates of electrically insulating material mounted within the other end of said tubular electrode and facing each other on opposite sides of the axis of said tubular member, an edge of each of said insulating support members in contact with said first apertured plate member, a tubular cathode electrode supported within and transversely to the axis 55 of said tubular electrode by said insulating support members, and a second apertured metal plate member fixed within said tubular electrode to said insulating support members between said cathode electrode and said first metal plate member, said first and second metal plate members each having an aperture therethrough on the axis of said tubular members and aligned with a surface portion of said cathode electrode.
4. An electron gun for a cathode ray tube, said electron gun comprising, a tubular electrode, a pair of support members of electrically insulating material supported

within said tubular electrode, a tubular cathode electrode supported within and transversely to the axis of said tubular electrode and by said insulating support members, and an apertured plate electrode supported within said tubular electrode by said insulating support members adjacent said cathode electrode, said tubular electrode having an aperture in the side wall thereof; and lead members connected to one of said electrodes within said tubular member and passing through said aperture in the side wall thereof.

5. An electron gun for a cathode ray tube, said electron gun comprising, a tubular electrode, a first apertured metal plate member fixed within and transversely across said tubular member, a pair of support members of electrically insulating material mounted within said tubular electrode on opposite sides of the axis thereof in contact with said transverse metal plate member, a tubular cathode electrode supported within and transversely to the axis of said tubular electrode and by said insulating support members, and a second apertured metal plate member supported within said tubular electrode by said insulating support members between said cathode electrode and said first metal plate member, said tubular electrode having an aperture in the side wall thereof; and lead members connected to one of said electrodes within said tubular member and passing through said aperture in the side wall thereof.

6. An electron gun for a cathode ray tube comprising, a tubular electrode, a plate member fixed within and closing said tubular electrode adjacent one end thereof, said plate member having an aperture therethrough, a pair of support plates of electrically insulating material mounted within the other end of said tubular electrode and facing each other on opposite sides of the axis of said tubular member, an edge of each of said insulating support members in contact with said first apertured plate member, a tubular cathode electrode supported within

and transversely to the axis of said tubular electrode by said insulating support members, and a second tubular metal member fixed within said tubular electrode between said insulating support members and enclosing said tubular cathode electrode, said second tubular member having an aperture therethrough between a surface of said cathode electrode and said aperture in said plate member.

7. An electron gun for a cathode ray tube, said electron gun comprising, a tubular electrode, a metal plate member fixed within and transversely across said tubular member, said plate member having an aperture therethrough, a pair of support members of electrically insulating material mounted within said tubular electrode on opposite sides of the axis thereof in contact with said transverse metal plate member, a tubular cathode electrode supported within and transversely to the axis of said tubular electrode and by said insulating support members, and a second tubular metal electrode member supported within said tubular electrode between said insulating support members and enclosing said cathode electrode, said second tubular electrode member having an aperture through the wall thereof aligned with said aperture in said metal plate member and a surface portion of said tubular cathode electrode; said cathode surface portion having a coating of thermionic emitting material thereon.
